US00D831760S

(12) **United States Design Patent** (10) Patent No.: **US D831,760 S**
(45) Date of Patent: **** Oct. 23, 2018**

(54) **WEIGHT TRAINING MACHINE**

(71) Applicants: **Zsolt Safranka**, Gyongyospata (HU);
Robert Kormos, Gyongyos (HU);
Máté Varga, Budapest (HU)

(72) Inventor: **Zsolt Safranka**, Gyongyospata (HU)

(**) Term: **15 Years**

(21) Appl. No.: **35/503,295**

(22) Filed: **Apr. 3, 2017**

(80) **Hague Agreement Data**

Int. Filing Date: **Apr. 3, 2017**

Int. Reg. No.: **DM/096591**

Int. Reg. Date: **Apr. 3, 2017**

Int. Reg. Pub. Date: **Jul. 7, 2017**

(51) **LOC (11) Cl. 21-02**

(52) **U.S. Cl.**

USPC **D21/686**

(58) **Field of Classification Search**

USPC D21/673, 686

CPC A63B 21/4035; A63B 21/4023; A63B
21/0601; A63B 21/00072; A61B 5/103
